A. C. KLECKNER

PORTABLE LAMP

Filed Jan. 27, 1922

Inventor
Arthur C. Kleckner
Williams, Bradbury,
McCalb & Pierce Atty

UNITED STATES PATENT OFFICE.

ARTHUR C. KLECKNER, OF RACINE, WISCONSIN, ASSIGNOR TO WEBSTER ELECTRIC COMPANY, OF RACINE, WISCONSIN, A CORPORATION OF WISCONSIN.

PORTABLE LAMP.

Application filed January 27, 1922. Serial No. 532,150.

To all whom it may concern:

Be it known that I, ARTHUR C. KLECKNER, a citizen of the United States, and resident of Racine, in the county of Racine 5 and State of Wisconsin, have invented certain new and useful Improvements in Portable Lamps, of which the following is a full, clear, concise, and exact description, reference being had to the accompanying 10 drawings, forming a part of this specification.

This invention relates to portable lamps of the type commonly employed about automobiles, and particularly to the type of 15 portable lamp in which a magnet is provided by means of which the lamp is caused to adhere to any iron or steel portion of the machine.

The object of the invention is to provide 20 a portable lamp of this character which shall be compact, in which the parts will not be subject to derangement, and in which the minimum number of parts shall be employed.

One of the features of the invention is the manner of forming the lamp socket of 25 portions inturned from the flange of the magnet housing.

Another feature of the invention is the 30 improved manner of joining together the leading in conductors, the terminals of the magnet winding, and the lamp socket terminals.

Other features and advantages will appear as the description of the invention progresses.

In the drawings,

Figure 1 is a side elevation of the lamp;

Figure 2 is a section substantially on the 40 line 2-2 of Figure 1;

Figure 3 is a section at right angles to Figure 2, and

Figure 4 is a section on the line 4-4 of Figure 3.

Referring now to the drawings, 45 represents the magnet housing which is generally cylindrical in cross section. Centrally positioned within the housing is the magnet core 11 provided with the pole piece 12. Se- 50 cured to the core 11 at the end remote from the pole piece 12 is a washer 13 of magnetizable material, the end of the core being

secured to the washer by having its end inserted through an opening in the washer and the edges thereof upset or peened over, 55 as indicated at 14.

Positioned above and below, respectively, of the washer 13 are the insulating strips 15 and 16. Adjacent to its opposite edges, the washer 13 is cut away, and for the cut-away 60 portions similar portions of insulating material are provided as indicated at 17 and 18. At 19 and 20 are indicated the terminal contacts of the lamp socket. These contacts 19 and 20 are carried at the ends of curved 65 metallic strips 21 and 22, respectively of flexible material, the ends of the strips 21 and 22 remote from the contacts being secured to the insulating strips 15 and 16 by means of the hollow rivets 23, each of 70 which passes through the strips 16, 15, and one of the strips 21 or 22. Two rivets are provided for attaching each of the strips 21 or 22 to the supporting strips 15 and 16. The hollow rivets provide openings through 75 which the terminals of the magnet coil 24 may be carried upwardly and into engagement with the strips 21 and 22 respectively.

The leading in conductors 25 and 26 have their terminals also brought into engagement with the strips 21 and 22, respectively, 80 at a point adjacent to the coil terminal and the terminals of both the leading in conductors, and the coil may be secured to the strip 21 or 22, as the case may be, by a drop 85 of solder.

The housing 10 is shouldered as indicated at 27 to provide a stop, limiting the upward movement of the magnet assembly into the housing. After the magnet assembly has 90 been placed in the housing, a split washer 28 is inserted in the groove 29 in the housing and by its engagement with the insulating washer 30 adjacent to the pole piece 12 maintains the magnet assembly within 95 the housing.

The housing at its upper edge has an in-turned flange 31. Integral with the flange 31 at opposite sides thereof are the downwardly extending ears 32, each of which is 100 provided with a bayonet slot 33. These ears 32 are slightly curved and together form a socket for the reception of the lamp base 34, as indicated in Figure 2. The bayonet slots

33 are arranged to receive the lugs 35 projecting from the opposite sides of the base 34 and maintain the lamp in position. When the lamp is in position with the lugs 35 within 5 in the offset portions of the slots 33, the terminals 36 of the lamp will be in engagement with the terminals 19 and 20 of the lamp socket, respectively. It should be here noted that the particular type of socket 10 herein disclosed is provided for the double contact type of lamp. However, with obvious modifications, it can be arranged to be employed with a single contact type of lamp.

15 A lamp shield 37 is provided, the open end of which fits snugly about the shouldered portion of the base member 10. The shield 37 on one side thereof and opposite the bulb of the lamp is cut away to provide an opening 38 through which the rays from the light 20 may shine.

Projecting inwardly from the side wall of the housing 10 is a lug 39, and the members 13, 15 and 16 are provided with aligned 25 notches to receive this lug 39 in order to definitely determine the rotary position of the magnet assembly within the housing. This assures that the contacts 19 and 20 will 30 always be in a position to be engaged by the lamp terminal contacts 36 when the lamp is inserted in the socket.

While in the above description and in the drawings but a single embodiment of the invention is disclosed, it is to be understood 35 that applicant contemplates modifications of certain of the details and the invention is, therefore, limited merely by the scope of the appended claim.

What I claim as new and desire to secure by Letters Patent of the United States is: 40

In a portable lamp, a substantially cylindrical housing, lamp socket contacts within said housing, an inwardly extending flange at one end of said housing, portions integral with said flange at opposite sides thereof 45 re-bent to lie substantially parallel with the walls of said housing and fashioned to form a lamp socket, a magnet coil within said housing, a core for said coil, a disc of magnetizable material at one end of said core 50 and at substantially right angles thereto, strips of insulating material, one at each side of said disc, hollow rivets extending through said strips for securing said strips, terminals for said coil extending through said hollow 55 rivets, a projection in said housing, notches in said magnetizable disc, said projection being adapted to engage with said notches in the magnetizable disc and insulating strips to determine the rotary position of the 60 magnet assembly within the housing, a split washer, a groove in said housing in which said split washer is inserted, an insulating washer in said groove, said split washer engaging with said insulating washer positioned 65 therebelow for the purpose of maintaining the magnet assembly within said housing, leading in conductors and means for securing the respective terminals of said coil and said conductors to said contacts. 70

In witness whereof, I hereunto subscribe my name this 19th day of January, 1922.

ARTHUR C. KLECKNER.
